ARTIFICIAL TOOTH

Max Marder, Paris, France

Application June 7, 1955, Serial No. 513,695

Claims priority, application France November 10, 1951

5 Claims. (Cl. 32—10)

The present invention relates to artificial teeth to be used by human beings.

More particularly, the present invention relates to facings of artificial teeth.

The present application is a continuation-in-part of application Serial No. 301,744 filed July 30, 1952, and now abandoned and entitled "Artificial Tooth," of application Serial No. 301,745, filed July 30, 1952, and now abandoned, and entitled "Artificial Teeth," and of application Serial No. 272,920, filed February 23, 1952, and now abandoned and entitled "Artificial Tooth."

In the art of artificial teeth, the most desirable results are produced when an artificial tooth, or at least the visible facing thereof, resembles a natural tooth so closely as to be indistinguishable therefrom. Thus far, this result has not been produced because conventional facings of artificial teeth are made of translucent materials which to the naked eye appear darker than natural teeth because the facings appear to have the color of the cement located behind the facing.

One of the objects of the present invention is to provide an artificial tooth facing which, when in use, resembles a natural tooth so closely as to be indistinguishable therefrom.

Another object of the present invention is to provide an artificial tooth facing with a light reflecting and diffracting means capable of giving the facing a natural appearance.

A further object of the present invention is to provide a light reflecting and diffracting means of the above type which at the same time serves to improve the strength of the artificial tooth and the security with which it is mounted.

With the above objects in view the present invention mainly consists of an artificial tooth which includes a translucent facing having a front surface adapted to be exposed when in use and a rear surface adapted to be joined to a support for the facing. A foraminous diffracting and reflecting sheet means, preferably made up of silver coated filaments of circular cross section, engages the facing and is located adjacent the rear surface of the facing for reflecting and diffracting light passing through the front surface thereof into the facing back through the facing and out through the front surface thereof and for giving to the facing a coloring closely approximating that of a natural tooth.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a sectional view taken in a horizontal plane through a vertically positioned facing constructed in accordance with the present invention;

2

Fig. 2 is a perspective view of another embodiment of a facing of the present invention as seen when looking toward the rear surface thereof;

Fig. 3 is a side elevational view of another embodiment of a facing constructed in accordance with the present invention;

Fig. 4 is a sectional view taken along line 4—4 of Fig. 3 in the direction of the arrows;

Fig. 5 is a partly sectional view taken along line 5—5 of Fig. 3 in the direction of the arrows; and

Fig. 6 is a sectional view on an enlarged scale corresponding to Fig. 4 and illustrating the principle on which the invention is based.

The present invention is limited to facings for artificial teeth, and these facings can be supported in a conventional manner. The facings are made of a translucent material so that light can pass therethrough. Thus the facing may be made of a translucent ceramic material such as porcelain or of a translucent synthetic resin such as an acrylic resin. A natural tooth does not have a uniform color, and therefore the material of the facing of the present invention is not relied upon to give the facing the coloring which it appears to have when used. Instead, a foraminous sheet means, such as a gauze sheet, is in engagement with the facing of the invention, is located adjacent the rear face thereof, and has an extremely white color so that the coloring of the facing of the invention is provided by light reflected with diffraction from this foraminous sheet means back through the facing toward the observer. In this way, as will be apparent from the description which follows, the facing of the invention has a uniform color which very closely approximates the coloring of a natural tooth. The reflected rays cross each other and mask the darker elements behind the facing. It is possible to manufacture the facings of the invention by molding them in suitably shaped molds.

Referring to Fig. 1, the facing 10 shown is made of any of the above mentioned translucent materials and has a foraminous sheet means 11 embedded therein. It will be noted that the sheet means 11 is located adjacent the rear face 12 of the facing 10 and has an omega cross section. In the remainder of this specification it is to be understood that an omega cross section signifies a shape corresponding to that of the Greek capital letter omega. This sheet means 11 is preferably in the form of a metallic gauze consisting of a mesh of extremely fine filaments. As was pointed out above the best results are obtained by a foraminous sheet means which is as white as possible. Thus, the metal of the gauze sheet cannot be platinum, for example, because such a metal is gray rather than white. It is preferred to make the gauze sheet 11 of wire filaments which are coated with silver. This latter construction has been found in practice to give the best possible results. The facing 10 shown in Fig. 1 may be supported on a bridgework or the like in any conventional manner.

Fig. 2 shows a facing 13 made of any of the above materials and formed in its rear face with an elongated groove 14 which gives the rear face an omega-shaped cross section. This groove 14 is adapted to receive a post of a support in a known way for mounting the facing. Against the rear surface 15 of the facing 13 is located the foraminous sheet means 16 which is preferably in the form of a metallic gauze sheet made up of a fine mesh work of silver coated filaments. It will be noted that the sheet means 16 covers the surface of the groove 14 in addition to a substantial portion of rear face 15 beyond groove 14. The sheet means 16 may be joined to the facing 13 as by being partially embedded therein during the molding thereof, or any adhesive may be used for this purpose. As was pointed out above and as will be further discussed below the foraminous sheet means

of the invention gives the facing a very natural coloring. In the embodiment of Fig. 1, the sheet means 11 performs the additional function of reinforcing the facing, and in the embodiment of Fig. 2 the sheet means also reinforces the facing and additionally provides it with a rough rear surface which increases the security of the mounting of the facing. That is, when an adhesive cooperates with the irregular rear surface of the facing of Fig. 2 to fasten this facing to a support, the bond is much stronger than would be the case if rear surface 15 were smooth. The rough rear surface is provided by pressing the sheet means against the rear surface of the facing while the latter is still plastic, and the material of the facing flows through the spaces between the filaments to provide the facing with rearwardly extending projections as shown in Fig. 6.

In the embodiment shown in Figs. 3-5, the facing 17 has a rear surface made up of a rear surface portion 18 and a rear surface portion 19, these latter rear surface portions being substantially at right angles to each other. Facing 17 is made of any of the above mentioned translucent materials. Only the rear surface portion 19 is formed with an elongated groove 20 to give rear surface portion 19 an omega-shaped cross section. Fig. 3 shows in dot-dash lines a conventional support 21 carrying the facing 17 and having a post of omega cross section mating with and fitting into the groove 20. A foraminous sheet means is embedded within the facing 17 closely adjacent to the rear face 18, 19 thereof, as shown in Figs. 3-5. This foraminous sheet means is preferably a metallic gauze as described above and includes a plane portion 22 located adjacent the rear surface portion 18 and a portion 23 of omega cross section located adjacent rear surface 19 and conforming closely to the groove 20, as shown in Fig. 4.

As is evident from the enlarged sectional view shown in Fig. 6, the gauze sheet which forms the foraminous sheet means of the invention is composed of filaments 24 which are coated with silver and which are of circular cross section. This gauze sheet is pressed into the rear surface of the casing facing while the material thereof is still plastic to provide the facing with rearwardly extending projections surrounded by the filaments of the gauze sheet.

The principle of the invention can be understood from Fig. 6 with respect to the parallel light rays A and B of monochromatic light which move in the direction of the arrows toward the facing of the invention. As is evident from Fig. 6 parts of these light rays are reflected from the front surface of the facing as light rays A₁ and B₁. The remainder of these light rays enter into the facing and are refracted to form the light rays A₂ and B₂, respectively. The light ray B₂ strikes one of the filaments and then moves back through the facing toward the front surface thereof as the light ray B₃, this latter light ray being refracted again at the front surface of the facing and emerging as light ray B₄.

On the other hand, the light ray A₂ encounters another filament 24 and then moves back toward the front surface of the facing as light ray A₃, this latter light ray being refracted at the front surface of the facing and emerging as light ray A₄. It will be noted that the light rays A₂ and A₃ cross over the light rays B₃ and B₂. When it is considered that an infinite number of light rays move in the manner indicated for the light rays A and B and that these light rays cross each other in the material of the facing an infinite number of times, it will be understood that these light rays serve to mask any dark colors of the elements which carry the facing so that these dark colors cannot give the facing an unnatural appearance.

It should also be noted that the cross sectional area of the projections of the facing which extend rearwardly through the gauze sheet is substantially smaller than the cross sectional area of the filaments which make up this

sheet. This is a further feature which contributes to the desired results.

It has been found in actual practice that the above described structure provides an artificial tooth facing which cannot be distinguished from a natural tooth when in use. This result is obtained by the translucency of the facing and by the extreme whiteness of the silver coated filaments of the foraminous sheet means.

It will be understood that each of the elements described above, or two or more together, may also find a useful application in other types of artificial teeth differing from the types described above.

While the invention has been illustrated and described as embodied in facings for artificial teeth, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. For use in an artificial tooth, in combination, a facing having a front surface adapted to be exposed when in use and a rear surface adapted to be joined to a support for the facing, said facing being made of a translucent molded material through which light can pass; and a gauze sheet of a light color engaging said facing and located adjacent the rear surface thereof for diffracting and reflecting light passing through said front surface of said facing into the latter back through said facing and out through said front surface thereof and for giving to the facing a coloring closely approximating that of a natural tooth.

2. For use in an artificial tooth, in combination, a facing having a front surface adapted to be exposed when in use and a rear surface adapted to be joined to a support for the facing, said facing being made of a translucent molded material through which light can pass; and a gauze sheet of a light color engaging said facing and located adjacent the rear surface thereof for diffracting and reflecting light passing through said front surface of said facing into the latter back through said facing and out through said front surface thereof and for giving to the facing a coloring closely approximating that of a natural tooth, said rear surface of said facing having a plurality of projections which extend rearwardly through said gauze sheet.

3. For use in an artificial tooth, in combination, a facing having a front surface adapted to be exposed when in use and a rear surface adapted to be joined to a support for the facing, said facing being made of a translucent molded material through which light can pass; and a gauze sheet of a light color composed of individual metallic filaments of circular cross section, engaging said facing and located adjacent the rear surface thereof for diffracting and reflecting light passing through said front surface of said facing into the latter back through said facing and out through said front surface thereof and for giving to the facing a coloring closely approximating that of a natural tooth.

4. For use in an artificial tooth, in combination, a facing having a front surface adapted to be exposed when in use and a rear surface adapted to be joined to a support for the facing, said facing being made of a translucent molded material through which light can pass; and a gauze sheet of a pure white color composed of individual silver coated filaments of circular cross section,

engaging said facing and located adjacent the rear surface thereof for diffracting and reflecting light passing through said front surface of said facing into the latter back through said facing and out through said front surface thereof and for giving to the facing a coloring closely approximating that of a natural tooth.

5. A process for manufacturing a facing for an artificial tooth, comprising the steps of molding a facing from a translucent material; and pressing a gauze sheet

into the rear surface of the facing, while the material thereof is still plastic, until the rear surface is provided with projections extending through the gauze sheet.
